US00D894177S

(12) **United States Design Patent** (10) **Patent No.:** **US D894,177 S**
(45) **Date of Patent:** **** Aug. 25, 2020**

(54) **NOTEBOOK COMPUTER**

(71) Applicants: **Jyh-Chyang Tzou**, Taipei (TW);
Chun-Ting Lee, Taipei (TW);
Yuan-Ping Chu, Taipei (TW);
Yao-Hsien Yang, Taipei (TW);
Pai-Feng Chen, Taipei (TW)

(72) Inventors: **Jyh-Chyang Tzou**, Taipei (TW);
Chun-Ting Lee, Taipei (TW);
Yuan-Ping Chu, Taipei (TW);
Yao-Hsien Yang, Taipei (TW);
Pai-Feng Chen, Taipei (TW)

(73) Assignee: **COMPAL ELECTRONICS, INC.**,
Taipei (TW)

(**) Term: **15 Years**

(21) Appl. No.: **29/629,569**

(22) Filed: **Dec. 14, 2017**

(51) LOC (12) Cl. **14-02**

(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a left side view thereof;

FIG. 5 is a right side view thereof;

FIG. 6 is a top view thereof;

FIG. 7 is an enlarged view thereof of the portion indicated in FIG. 1;

FIG. 8 is an enlarged view thereof of the portion indicated in FIG. 1;

FIG. 9 is an enlarged view thereof of the portion indicated in FIG. 2;

FIG. 10 is an enlarged view thereof of the portion indicated in FIG. 2;

FIG. 11 is an enlarged view thereof of the portion indicated in FIG. 3;

FIG. 12 is an enlarged view thereof of the portion indicated in FIG. 4; and,

FIG. 13 is an enlarged view thereof of the portion indicated in FIG. 4.

(Continued)

The broken lines shown in the drawings illustrate portions of the notebook computer that form no part of the claimed design.

1 Claim, 13 Drawing Sheets
